UNITED STATES PATENT OFFICE.

PERCIVAL W. SHEPARD, OF BOERNE, TEXAS.

ADVERTISING SIGN.

Application filed July 7, 1922. Serial No. 573,366.

To all whom it may concern:

Be it known that I, PERCIVAL W. SHEPARD, a citizen of the United States, residing at Boerne, in the county of Kendall and State of Texas, have invented certain new and useful Improvements in Advertising Signs, of which the following is a specification.

This invention relates to improvements in advertising signs.

The value of a sign as an advertising medium depends in a large measure upon its power to attract attention, and this in turn is dependent upon various features, chief among which may be mentioned light, color, and motion, and where a sign embodies all of these features it attracts and holds the attention with more certainty than where one or another of these features is lacking.

20 A sign operating with the appearance of motion is more certain to attract attention than a sign from which this feature is absent. The display of colors, particularly when under conditions of illumination, is also a feature which greatly enhances the attractiveness of an advertising sign. Where the colors are more or less frequently changed, the attractiveness is greatly enhanced. The primary object of the present 30 invention is therefore to provide an advertising sign which in its operation will exhibit the appearance of motion attended by constantly changing lighting and color effects thus combining all of the features above referred to and producing a sign capable of attracting and holding the attention of the observer with certainty and for such period of time as to induce him to read the message conveyed by the advertising 40 matter of the sign.

Heretofore changes in lighting and color effects have been produced principally by the employment of flashing mechanisms and variously colored light bulbs or the like but such an arrangement is expensive to install and operate and the field of variations in effects displayed is greatly limited. Therefore it is another important object of the present invention to obviate the employment of flashing mechanisms and at the same time to provide a simple and inexpensive means for producing a constantly changing display of colors under conditions of illumination.

55 Another objection attending the use of

signs employing colored lights and flashing mechanism associated therewith is that there must usually be an abrupt change from one color to another. Therefore it is another important object of the invention to provide means whereby, throughout the area of the sign display surface, there will be a continually changing or varying display of colors and tints, the colors blending and gradually changing through a shading off into one another, so that a most pleasing effect is produced. In this connection the invention contemplates the employment of color media embracing for example certain of the primary colors and functioning in such a manner as to effect a blending of these colors to produce all possible spectral combinations thereof and thus display all colors and graduations of colors of the solar spectrum.

Another object of the invention is to provide a sign construction of such nature that the color and lighting effects to be displayed thereby may be varied at will by substitution and rearrangement of parts.

Another object of the invention is to provide a sign which while more attractive than the majority of signs embodying expensive flashing mechanisms, will be inexpensive to construct, install, and maintain in operation.

In the accompanying drawings:

Figure 1 is a perspective view of the sign embodying the invention;

Fig. 2 is a horizontal sectional view through the sign;

Fig. 3 is a group perspective view illustrating the sign character display surface, the diffractive medium, the light-ray penning medium and the color imparting medium in substantially their proper relative positions;

Fig. 4 is a vertical front to rear sectional view on the line 4-4 of Fig. 2 looking in the direction indicated by the arrows;

Fig. 5 is a view partly in section and partly in side elevation illustrating the tensioning roll for the color imparting medium and the means supporting this roll;

Fig. 6 is a fragmentary perspective view illustrating a portion of the structure shown in Fig. 5;

Fig. 7 is a perspective view illustrating in a general way a modification of the invention;

Fig. 8 is a view similar to Fig. 2 illustrating a modification of the invention;

Fig. 9 is a view similar to Fig. 5 illustrating a modified form of tensioning means;

5 Fig. 10 is a view similar to Fig. 7 illustrating a modification of the color imparting medium.

The sign comprises a casing which is indicated in general by the numeral 1 and 10 which comprises a front indicated in general by the numeral 2, end walls 3, a rear wall 4, a top 5 and a bottom 6. The front 2 of the casing is preferably in the nature of a frame 7 bolted or otherwise secured, as at 8, 15 to the open front of the casing and rabbeted, as at 9, or otherwise formed to accommodate and support certain members which will now be described. The sign display surface consists essentially of three component parts or 20 panes, indicated one by the numeral 10, and another by the numeral 11, and the third by the numeral 12. The member 10 may be in the nature of a pane of glass, or a sheet of celluloid, or any other transparent, 25 translucent or opaque material, and bears sign characters indicated by the numeral 13 which may be painted, cut out, or otherwise depicted upon or in the said pane. As a general proposition the sign character will 30 be transparent or translucent and the remaining area of the pane will be more or less opaque, or if found desirable the sign characters may be more or less opaque, and the remaining area of the pane may be transparent or translucent. Where the sign characters are painted or similarly depicted upon the pane, the advertising matter may of 35 course be varied from time to time without the necessity of substituting a new pane, or it may be found desirable to employ cloth, paper, or some other similar material instead of glass in producing this element of the display surface.

40 The member 11 of the display surface 45 preferably comprises a pane of glass, one or both faces of which is molded or otherwise provided with numerous prismatic projections or depressions as clearly shown in Fig. 3 of the drawings and indicated by the 50 numeral 14.

55 The member 12 of the display surface comprises a pane or sheet of some opaque or translucent material and is provided with a number of small perforations 15 extending over its entire area. If desired, instead of forming perforations in an opaque pane or sheet the pane or sheet 12 may be of opaque material except for transparent or translucent punctiform areas corresponding to the 60 perforations 15. In any event the pane 12, when employed, serves to transmit the light rays from the source of light to the panes 10 and 11 in the form of pencils and it may therefore be considered as a light ray pencilling medium. The prismatic pane 11 may

be considered as a diffractive medium and therefore the sign display surface as a whole may be said to consist of a sign character display surface proper, a diffractive medium, and a light ray pencilling medium and at 70 this point it will be evident that the light rays from the source of illumination, comprising electric bulbs 16 suitably arranged within the casing 1, pencilled by the perforations or transparent areas of the pane 12 will 75 be variously reflected in passing through the small prisms upon the face or faces of the pane 11 before reaching the pane 10. It will also be apparent at this point that if the source of illumination or, as is more strictly 80 speaking the case in the present arrangement, the color medium, is given motion, the constant shifting of the light rays will, by reason of the component parts of the display surface, be exhibited with a scintillating effect most pleasing to the eye. 85

90 The color imparting medium is indicated in general by the numeral 17 and comprises a band of flexible, transparent or translucent material, indicated by the numeral 18, and provided with color fields 19, 20 and 21, which may respectively be red, yellow and blue. These color fields in the embodiment 95 of the invention illustrated in Fig. 3 of the drawings, are diagonally arranged upon the band 18 and are of regular marginal outline. However, the fields might be of irregular contour and extend otherwise than in a general diagonal direction. The relatively adjacent ones of the fields are separated by intervening transparent or translucent fields 22 which are relatively narrow and which of course permit the passage of light rays, the light rays passing through the other 100 color fields being of course correspondingly tinted. 105

110 In the form of the invention shown in Figs. 1 to 6, inclusive, the band 18 which is endless, is passed about a roll 23 and a roll 24, and its intermediate stretches, one indicated by the numeral 25 and the other by the 115 numeral 26, are passed respectively over idle rolls 27 and 28 journaled in upright position within the casing at the ends thereof and immediately rearwardly or inwardly of the sign display surface within the front 2 of the casing. The roll 23 is provided at its lower end with a pinion 29 which is in mesh with a gear 30 carried at the lower end of a barrel 31 rotatably mounted within the rear portion of the casing and upon the bottom 6 thereof. The numeral 32 indicates an electric motor having the usual shaft 33 which is provided with a worm 34 meshing with a worm gear 35 upon the upper end of the barrel 31. In this manner means is provided for imparting travel to the band 18 and it will be evident that the stretches 25 and 26 of the band will travel in opposite 120 directions past each other. 125

The roll 24 constitutes a tensioning roll and is best illustrated in Figs. 5 and 6 of the drawings. This roll comprises a hollow body 36 having heads 37 fitted into its ends and receiving the ends of a spindle 38. The said ends of the spindle project beyond the respective heads 37, and the upper end of the spindle is provided with a reduced portion 39, as best shown in Fig. 6. The support for the tensioning roll comprises a resilient strip 40 of metal to the upper and lower ends of which are hinged, as at 41, bearing leaves indicated, one by the numeral 42 and the other by the numeral 43. The projecting lower end of the spindle 39 is rotatably engaged in a bearing opening 44 provided in the lower leaf 43, and the upper leaf 42 is formed with a key-hole slot indicated by the numeral 45, the larger end of which is of a diameter to permit of the passage thereto of the projecting upper end of the spindle 38 and the narrower portion of which is designed to accommodate the reduced portion 39 of the said projecting end of the spindle. A threaded stem 46, or if desired a bolt, projects from the intermediate portion of the strip 40 and through the rear wall 4 of the casing 1, and an adjusting nut 47 is threaded on to the rear end of this stem and bears against the rear face of the wall 4 and may be rotated to adjust the stem through the casing 1 and thus exert a greater or less tension upon the band 18 passing about the roll 24.

The color fields 19, 20 and 21 may be considered as spectral color fields, and the fields 22 as the white light fields, and it will be evident that when the sign is in operation and the stretches 25 and 26 of the band 18 travel past each other in opposite directions, there will be a continually varying overlapping of the fields of the two stretches. Thus when the red and yellow fields of the two stretches are brought substantially opposite each other, the rays from the source of light will be tinted orange; when the yellow and blue fields are opposite each other the rays will be tinted green; and, when the red and blue fields are opposite each other the rays will be tinted violet or purple. When the corresponding spectral color areas are brought opposite each other as for example the red opposite the red, the respective primary color will be intensified. On the other hand when the white light areas are brought opposite any of the spectral color areas, the rays passing through the corresponding last-mentioned color area will be tinted a lighter shade of such color. Also as non-corresponding ones of the spectral color fields of the two stretches begin to overlap in their passage past each other not only will the primary and various secondary colors be produced by a composition of the different color fields but there will also be produced

various shades of these colors. Thus as the stretches of the color imparting medium pass each other in the manner stated, the display surface of the sign will be illuminated with a constantly shifting and continually varying array of colors embracing practically the entire solar spectrum.

In the form of the invention above described the stretches 25 and 26 of the band comprising the color imparting medium travel longitudinally of the front of the casing but if desired an arrangement such as shown in Fig. 7 of the drawings may be made use of and in this figure the numerals 48 and 49 indicate respectively rolls which are journaled in the upper and lower portions of the casing at the front thereof. In this arrangement the color imparting medium comprises a relatively broad band 50 which is passed over the rolls 48 and 49 and has front and rear stretches 51 and 52 which travel in opposite directions and vertically. A pinion 53 is fixed upon the end of the roll 49 and meshes with an idle gear 54 mounted within the casing, this gear being driven from a pinion 55 fixed upon the motor shaft which is indicated by the numeral 56. The band 50 is provided with color fields 57, 58 and 59 and with intervening white light fields 60, and in this embodiment the fields are of more or less irregular contour, following substantially the figure of a sinusoidal curve.

In the previously described embodiments of the invention two stretches of the color imparting band are caused to travel between the source of illumination and the sign front, but in that form of the invention shown in Figs. 8 and 9 of the drawings, the band, which is indicated by the numeral 61, is trained about idle rolls 62 at opposite ends of the front of the casing of the sign, and about other idle rolls 63 located at the opposite ends of the back of the casing so that a single stretch only of the band, indicated by the numeral 64, and passing between the rolls 62, is caused to travel between the source of illumination and the sign front. While in this arrangement there will not be produced the same blending of colors as in the previously described forms, nevertheless the effect is pleasing to the eye. In this form the sources of illumination are illustrated in a general way and indicated by the numeral 65, and the casing is provided with a front constructed and arranged substantially in the same manner as the front previously described. Also in this form of the invention the band 61 is passed about an idle roll 66 positioned somewhat in advance and at one side of one of the rolls 63 and relatively close thereto, and at a point adjacent the roll 66, the band is passed about a tensioning roll which is indicated by the numeral 67. The roll 67 is

mounted in a bearing yoke 68, and threaded stems 69 extend from this yoke through openings in the rear wall of the casing for the sign and have tensioning nuts 70 threaded thereon, springs 71 being arranged upon the stems between the rear wall of the casing and the said nuts so as to yieldably resist inward or forward movement of the stems through the openings in said wall. Of course, by adjusting the nuts 70, the tension imposed upon the band 61 may be varied.

In that form of the invention shown in Fig. 10 a band constituting a color imparting medium and indicated by the numeral 72 is provided and is arranged and actuated substantially in the same manner as the band shown in Fig. 7. In this instance, however, the color fields 73, 74 and 75 which correspond to the color fields 57, 58 and 59 of the band 50 extend generally in the direction of travel of the stretches of the band rather than diagonally or transversely of the line of travel, and they are spaced by intervening transparent areas 76 corresponding to the areas 60.

Having thus described the invention, what is claimed as new is:

1. In a sign, a display surface having a light ray transmitting portion, a source of illumination, and a light ray transmitting color medium comprising an endless band having stretches passing opposite each other between the source of illumination and the display surface and travelling in opposite directions, the band having a plurality of color fields extending in a series in the

general direction of travel of the band, the color fields extending substantially diagonally of the band, and all inclined in the same direction, the band having white light ray fields interposed between adjacent ones of the said color fields.

2. In a sign, a travelling band, and a tensioning means for the band comprising a roll about which the band is passed, a spindle supporting the roll and having projecting ends, one of which has a reduced portion, and a resilient member supported between its ends, leaves hinged to the ends of the resilient member and having bearing openings receiving the projecting ends of the spindle, the opening in one leaf having a portion of a diameter to permit of the passage of the spindle thereinto and another portion of less dimensions to receive the reduced portion of the spindle, and means coacting with the supporting means for the member for tensioning the same.

3. In a sign, a display surface having light ray transmitting portions defining sign characters, a diffractive medium comprising a faceted pane arranged in rear of the display surface, a perforated plate in rear of the diffractive pane constituting a light ray pencils medium, a light ray transmitting color medium comprising an endless band having its stretches arranged to pass each other in rear of the light ray pencils medium, and a source of illumination in rear of the said band.

In testimony whereof I affix my signature.
PERCIVAL W. SHEPHARD.
